(57) CLAIM

The ornamental design for a clothing article, as shown and described.

DESCRIPTION

FIG. 1 is a perspective view of a clothing article according to the present invention.

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings represent unclaimed subject matter and form no part of the claim.
